INFLATABLE NOVELTY HEAD GEAR

Elizabeth Ivon, 110 E. 36th St., New York, N.Y.

Filed Aug. 9, 1965, Ser. No. 86,514

Term of patent 14 years

(Cl. D34—15)

Fig. 1.

Fig. 2.

Fig. 3.

Fig. 4.

FIG. 1 is a front view of inflatable novelty head gear showing my design in uninflated condition;

FIG. 2 is a side view of the inflated novelty head gear in uninflated condition;

FIG. 3 is a plan view of the inflatable novelty head gear in inflated condition;

FIG. 4 is a front elevation of the inflatable novelty head gear in inflated condition.

The broken line portion seen in the figures is to indicate indeterminate length.

I claim:

The ornamental design for an inflatable novelty head gear, as shown and described.
